3 SHEETS—SHEET 3.

Inventor:

Raymond Hanus
By June Daniels de
Attorney.

UNITED STATES PATENT OFFICE.

RAYMOND HANUS, OF BRUSSELS, BELGIUM.

TYPEWRITER.

Application filed November 28, 1921. Serial No. 518,445.

To all whom it may concern:

Be it known that I, RAYMOND HANUS, a subject of the King of Belgium, residing at Brussels, Belgium, have invented certain new and useful Improvements in Type-writers, of which the following is a specification.

Commercial necessities require that it should be possible to write on a special single sheet which forms a check or control and also a copy, inscriptions which are made on a series of separate sheets. This is chiefly the case when it is desired to add the amounts of various receipts that have been written on the machine. Reproduction of these inscriptions on the control sheet is generally done by means of carbon paper, the separate sheets, such as for instance receipts, being introduced one after another into the paper support of the machine. The drawback of the said method is that the indications on the copy are spaced at a distance apart dependent upon the dimensions of the forms. In fact, the platen roller which carries the papers, must be moved to the extent of several notches, corresponding to line spaces, for making the inscription on a separate sheet and then on the next one.

These drawbacks are avoided in the present invention owing to the control sheet being driven by the ordinary mechanism which produces the advance or feed, that is to say to its being advanced to the extent of one notch equivalent to one line space for each return of the carriage, whilst the separate sheets are operated by an independent device which enables them to be moved on the carriage whilst the control sheet remains fixed.

Moreover, means is provided for cutting into separate sheets paper supplied from a continuous strip or roll.

The invention provides special devices for the case in which the separate sheets are moved by hand, or automatically by the return of the carriage.

It provides also special devices for the case in which only one line is to be inscribed on each of the separate sheets, or for that in which several lines of inscription are necessary.

The accompanying drawings illustrate by way of example several constructions according to the invention for the case in which the separate sheets are obtained by

cutting a roll of paper. In the description, the said separate sheets which in practice are for instance receipts, cheques, invoices, etc., are designated by the generic name of "forms."

Figure 1 is a general view of the invention, the forms being moved by a hand operated mechanism, for the case in which only one line of inscription is to be written on each form.

Figure 2 is a cross-section of Figure 1 and shows the principle of the invention. For the sake of clearness the thickness of the sheets has been greatly exaggerated.

Figure 3 shows a device automatically ensuring the movement of the paper by the return of the carriage, with one line of inscription per form.

Figure 4 shows the hand driving device for the case in which several lines of inscription are to be written on each form.

Figure 5 shows an automatic device for the latter case.

The carriage 1 which carries the sheets is moved in the usual manner on the frame 2 of the typewriter. On the said carriage are mounted: (1) the platen roller 3 on which are placed the copy sheet 4 and the carbon paper sheet 5 and (2) the apparatus which guides, drives, and cuts the forms. The roller 3 is rotated at each return of the carriage to an extent equal to a line space; and the said carriage comprises two plates or standards 6 and 6' which support the roll of forms 7, the paper guides and the feed roll shafts 8 and 8', and the device for cutting the typed sheets.

The first form 9 is introduced together with the carbon sheet 5 and the tally sheet 4 which is to form the copy, behind the platen 3 which is turned by means of a hand-wheel 10 until the sheets are brought in front of the type.

The sheets 4 and 5 are held on the platen 3 by means of the usual pressing or clamping devices. Two brackets 11 and 11' which are pivoted about pins 12 and 12' respectively and to which are secured the cutting device and one of the feed roll shafts 8 for guiding the paper 9 are then turned down on their pivot pins.

The device which will be hereinafter described ensuring the advance of the form 9, is operated until the line on which the inscription is to be made, is brought to the

level of the type. The brackets 11 and 11' are then turned upwards and held in raised position by means of catches 13 and 13' respectively. The form 9 is driven by the rubber feed rolls 14 slideable on the shafts 8 and 8'.

When only one line of inscription is to be written on the forms, and the advance of the paper 9 is effected by hand, the work is 10 done in the following manner:—

After having written the desired indications, the sheet 9 is moved by operating a handle 15 which drives a wheel 16 mounted on a spindle 17 on which is a toothed wheel 18 which engages with a wheel 19. The latter wheel acts on gears 20 and 21 mounted on the feed roll shafts 8' and 8 respectively. The shaft 8' is secured to the two plates 6 and 6', and the shaft 8 is mounted in the 20 brackets 11 and 11'.

In the case in which the inscription is made on any desired alignment of the form, and the latter has an arbitrary length, the handle 15 is operated until the sheet 9 is 25 brought to a mark indicating the height or level of the type. The inscription is then made, whereupon the operator continues to turn the wheel 16 until the lower edge of the form is brought to the level of the knife, 30 in order to enable it to be cut to the required length.

If however the typing is done on forms of a given size, on which only one line is typed, the wheel 16 is provided with a small recess 35 22 with which engages a roller 23 which is mounted on the end of a lever 24 constantly pulled upwards by a spring 25. This stop locks the advance or feed device, stops the 40 paper at the level of the knife, and fixes the alignment of the next form at the height or level required for making the necessary inscription.

It must be pointed out that for each size of forms, it is necessary to use a set of gear 45 wheels producing the desired special feed or advance.

If it is required to write several lines on one and the same form, and it is desired to obtain an exact line space on the latter, the 50 device shown in Figure 4 is adopted, in which on one and the same spindle 17 are mounted the wheel 16, the wheel 18 driving the feed roll shafts 8 and 8' (Figure 1), and a notched wheel 26 constructed substantially 55 similar to the one which effects the spacing of the platen 3. A roller 27 on a lever 28 passes, on a slight movement of the handle 15, from one notch of wheel 26 to the next, and the form 9 is therefore fed forward to 60 the extent of a line space, whilst the carbon paper sheet 5 and the copy 4 are fed forward to the same extent automatically by the return of the carriage.

A hand-operated cam or other device 59 18' of a suitable shape makes it possible to dis-

engage the lever 28 carrying the roller 27 when the marks indicating the line spaces are no longer necessary.

Another construction is shown in Figures 3 and 5. In this construction the return of 70 the carriage is utilized for producing the advance of the three sheets in the desired proportions.

To that end, a rack 29 is secured to the frame 2 by means of brackets 30. Under the 75 said rack travels a toothed wheel 31 mounted on a spindle 32 secured to the carriage 1 and transmitting the movement by means of a bevel wheel 34 to a gear wheel 33 and thence to the wheels 20 and 21, the latter 80 two being secured as before stated to the feed roll shafts 8' and 8 respectively. The said spindle 32 rotates in brackets 35 and 35' which form bearings.

The spindle 32 is provided with a free-wheel clutch 36 such that the bevel wheel 34 is rotated when the carriage 1 returns "to the line", and remains stationary when it is moved in the direction enabling indications to be written. A spring 37 keeps the 85 free wheel clutch 36 in engagement during the movement in the two directions of the carriage 1.

The length of the rack and the gear wheels are calculated for a given size of forms. 95 The line on which the indications are to be inscribed, will be brought direct to the level of the type, without it being necessary to make any new manœuvre. It will be seen that the return of the carriage feeds the 100 copy sheet 4 forward in the ordinary manner, to the extent of a line space, so that the inscription can be made on the next form.

If it is desired to write several lines on one and the same form, the device shown in 105 Figure 5 will be used. In such a case, in addition to the elements shown in Figure 3, will be used a device by means of which the free wheel clutch 36 can be disengaged and, by the same movement, the gear wheels controlling the movement of the platen 3 which carries the copy sheet, and the wheels which 110 drive the feed roll shafts 8 and 8'.

To that end, a key 38 is supported by a bracket 35' behind which it can be keyed. 115 This key can shift the movable member of the clutch 36 out of engagement with the fixed member thereof, by means of a yoke on said key which coacts with the grooved hub 39 of said movable clutch part. At the 120 same time the key acts on a lever 40 pivoted about a pin 40' and serving to shift a toothed wheel 41 into mesh with a wheel 49 and also with the wheel 33, the former of which is secured to the platen 3, while the latter controls the shafts 8 and 8'. When the movable part of the clutch 36 is disengaged, the bevel wheel 34 will cease to act on the wheel 20, so that the rack 29 will no longer act in 125 order to move the form 9. The gear wheels 130

are so calculated that the movement of the platen 3 to the extent of a line space produces an identical advance of the sheet 9.

On the key 38 being returned to the position illustrated, the rack 29 will act during the next return of the carriage 1 on the paper 9 which will be advanced to the amount required.

The device enabling the forms to be cut

- 10 after typing is shown in Figures 1 and 2. A circular knife 42 can rotate about a spindle 43 and is held in place by two cylindrical guides 44 and 44'; the knife could be constituted if necessary by a fine rigid blade.
- 15 The spindle 43 is mounted on a sleeve 45 which slides on a rod 46 of square or other cross-section. The knife blade passes through a slot provided in a bar 47. The paper 9 to be cut is pressed against the said bar by two rollers 48 and 48' mounted on the spindle 43. By sliding the carriage supporting the knife 42, on the guide 46, the form will be neatly cut in one operation to the desired size.
- 20 25 A suitable arrangement of the gear wheels makes it therefore possible to make inscriptions on forms of given length and at clearly specified alignment levels, the stoppage of the advance movement of the sheet 9 being marked exactly. Moreover, the apparatus can also be adapted for typing on sheets of any desired length, and at any point of the said sheets, the cutting and the inscription being done with the assistance of clearly
- 30 35 visible marks. Owing to the advance of the sheet 9 being independent of that of the copy 4, the latter will be moved at each return of the carriage only to the extent of one line space, whatever be the size of the form and 40 the position of the inscriptions, on the latter.

The apparatus could be fitted to any typewriters provided with a movable carriage, with or without automatic return.

- 45 45 What I claim is:

1. An apparatus for writing on a typewriter, on a single sheet, inscriptions made by the machine on a series of separate form sheets, comprising a carriage, a platen, two coacting feed rolls, a spindle driven by hand for rotating said rolls, a wheel keyed to the spindle provided with a single notch with which a pawl engages after each complete revolution of the said wheel, and means for ensuring angular movements of said wheel corresponding to the line spaces.

2. An apparatus for writing on a typewriter, on a single sheet, inscriptions made by the machine on a series of separate form sheets, comprising a carriage, a platen, two coacting feed rolls, a wheel keyed to a spindle provided with a single notch with which a pawl engages after each complete revolution of the said wheel, and a second wheel keyed on the same spindle having notches

indicating angular movements corresponding to the line spaces.

3. An apparatus for writing on a typewriter, on a single sheet, inscriptions made by the machine on a series of separate form sheets, comprising a carriage, a platen, two coacting feed rolls, and means for rotating said feed rolls independently of the platen, by the displacement of the carriage.

4. An apparatus for writing on a typewriter, on a single sheet, inscriptions made by the machine on a series of separate form sheets, comprising a carriage, a platen, two coacting feed rolls, a wheel for driving the aforesaid feed rolls independently of the platen, and means for rotating said wheel only during the return movement of the carriage.

5. An apparatus for writing on a typewriter, on a single sheet, inscriptions made by the machine on a series of separate form sheets, comprising a carriage, a platen, two coacting feed rolls, a wheel for rotating said feed rolls, a spindle provided with a free-wheel clutch, and means for rotating said spindle during the movement of the carriage.

6. An apparatus for writing on a typewriter, on a single sheet, inscriptions made by the machine on a series of separate form sheets, comprising a carriage, a platen, two coacting feed rolls, a spindle provided with a free-wheel clutch, a rack secured to the frame of the machine, and means for disengaging the free wheel clutch and at the same time coupling one of the aforesaid feed rolls with the platen.

7. An apparatus for writing on a typewriter, on a single sheet, inscriptions made by the machine on a series of separate form sheets, comprising a carriage, a platen, two coacting feed rolls, a spindle provided with a free-wheel clutch, a rack secured to the frame of the machine, and a key connected to disengage the free-wheel clutch from control of the aforesaid spindle.

8. An apparatus for writing on a typewriter, on a single sheet, inscriptions made by the machine on a strip of form sheets, comprising a carriage, a platen, two coacting feed rolls operable independently of the platen, a blade passing through a slot provided in a bar across which the strip of forms slides, and means for moving said blade along said bar to sever the separate forms from said strip.

9. An apparatus for writing on a typewriter, on a single sheet, inscriptions made by the machine on a strip of form sheets, comprising a carriage, a platen, two coacting feed rolls operable independently of the platen, a blade passing through a slot provided in a bar across which the strip of forms slides, a carriage carrying said blade and slidably on a rod disposed alongside

said bar, and means for pressing the strip of forms against said bar during the severing of the forms.

10. An apparatus for writing on a typewriter, on a single sheet, inscriptions made by the machine on a strip of form sheets, comprising a carriage, a platen, two coacting feed rolls operable independently of the platen, a blade passing through a slot provided in a bar across which the strip of

forms slides, a carriage carrying the said blade and slideable on a rod disposed alongside said bar, and rollers on the blade carriage for pressing the strip of forms against said bar during the severing of the forms. 15

In testimony whereof I affix my signature.

RAYMOND HANUS.
